Primary Examiner — Sheryl Lane*Assistant Examiner* — Ieisha N Price(74) *Attorney, Agent, or Firm* — JCIPRNET(57) **CLAIM**

The ornamental design for a shovel, as shown and described.

DESCRIPTION

FIG. 1 is a perspective view of a shovel showing our new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and

FIG. 8 is a perspective view thereof, showing the shovel in its contracted state; and,

FIG. 9 is a perspective view thereof, showing the shovel in its contracted and folded state.

The broken lines in the drawings illustrate portions of the shovel and form no part of the claimed design.

1 Claim, 8 Drawing Sheets(56)
